UNITED STATES PATENT OFFICE.

GUSTAF M. WESTMAN, OF NEW YORK, N. Y.

METHOD OF AND APPARATUS FOR GENERATING MOTIVE POWER.

SPECIFICATION forming part of Letters Patent No. 634,155, dated October 3, 1899.

Application filed June 20, 1896. Renewed January 23, 1899. Serial No. 703,202. (No model.)

To all whom it may concern:

Be it known that I, GUSTAF M. WESTMAN, a subject of the King of Sweden and Norway, residing in New York city, in the county and State of New York, have invented a new and Improved Apparatus for Generating Motive Power, of which the following is a full, clear, and exact description.

The object of the invention is to provide a new and improved apparatus for generating motive power in a very simple and economical manner. Heat is applied during expansion of the gaseous fluid that drives the motor, so as to obtain a superior result.

15 The construction and operation of the apparatus or motor are as hereinafter described.

Reference is to be had to the accompanying drawings, forming a part of this specification, in which similar characters of reference indicate corresponding parts in all the figures.

Figure 1 is a sectional side elevation of the improved apparatus on the line 1 1 of Fig. 3. Fig. 2 is a rear sectional side elevation of the same on the line 2 2 of Fig. 3. Fig. 3 is a plan view of the same. Fig. 4 is a sectional plan view of the motor, and Fig. 5 is a sectional side elevation of the same.

The improved apparatus is provided with a motor A in the form of a steam or gas turbine, such as shown and described in the application for Letters Patent of the United States, Serial No. 587,840, filed by me April 16, 1896.

The motor A (see Figs. 2, 4, and 5) is provided with a stationary disk A', the lower portion of which is fitted loosely into a correspondingly-shaped recess formed in the top of the turbine wheel A², disposed horizontally and inclosed with the said disk within a casing A³. In the stationary disk A' are arranged a series of radially-disposed passages A⁴, terminating at their inner ends in a central opening connected with the supply-pipe B, attached to the top of the disk A' and through which passes the gaseous fluid under pressure to and through the said passages A⁴. Each of the latter terminates in a series of channels A⁵, standing at angles to the passages A⁴ and discharging the fluid at their outer ends into the inner ends of the buckets A⁶ of the turbine wheel A².

The buckets A⁶ are preferably curved, as

indicated in dotted lines in Fig. 4, with the inner ends larger than the outer contracted ends, which latter discharge the motive agent approximately tangentially to the periphery of the wheel A². On the top of the stationary disk A' is arranged a steam-coil A⁷, made of pipe square in cross-section and with the runs closely fitted together, as plainly shown in Figs. 4 and 5, the said coil extending directly over the channels A⁵, so as to impart heat to the gaseous fluid during its travel through the said channels and while the fluid is in the free expanding state—that is, during actual expansion and before rendering work.

It is to be understood that when a fluid is expanded it cools rapidly, and in order to retain at least the same temperature of the expanded fluid as that it had before expansion is the object of the heater over the channels A⁵, so that the expanded fluid does not cool below the initial temperature it had on entering the motor. The fluid thus expanded without loss of heat passes into and through the buckets A⁶ to act thereon so as to rotate the wheel A². The exhaust from the buckets passes into the casing A³ and from the latter into the exhaust-pipe C. The rotary motion given to the wheel A² is transmitted by wheels to the main shaft D, which in turn is geared with a shaft D' for driving other machinery.

The exhaust-pipe C is connected with the intake-cylinder E of a compressor F of any approved construction and provided on its driving-shaft F' with a pulley F², connected by a belt F³ with a pulley F⁴, secured on a shaft F⁵, geared with the main shaft D of the motor A, so that when the latter is actuated the said compressor F is set in motion.

The motive agent is compressed in the intake low-pressure cylinder E and discharged to the compressing high-pressure cylinder E', connected at its outlet H with a reservoir I, in which the compressed fluid is stored. The reservoir I is connected by a pipe J with a heater K of any approved construction and connected with the inlet-pipe B of the motor A. The cylinders E and E' are provided with the usual water-jackets. The intercooler G is formed in the usual manner with pipes, through which circulates water.

L (see Fig. 2) is a coiled pipe arranged in

the shell or casing of heater K and designed for passage of steam.

Now it will be seen that when the apparatus is in motion the motor A drives the compressor F, so that the exhaust from the motor A is compressed and highly heated in the intake-cylinder E and then passed through the intercooler G to the compressing-cylinder E', less in size than the intake-cylinder E, so that higher compression takes place, and this highly-compressed fluid is stored in the reservoir I. The fluid passing from the reservoir I through the pipe J into the heater K is heated therein by means of a steam-coil L and again serves as the motive agent for driving the motor A. Thus the fluid employed is used over and over again by regenerating it, and part of the developed force is used for driving the air-compressor and the remainder is available for other purposes.

It is understood that the compression of the fluid can be made in two or more steps, and the fluid is cooled between the steps, but always stored in the reservoir before a heating, during free or initial expansion, takes place.

On account of the great velocity of the free expansion fluid it is desirable that the fluid during the free expansion period should pass through long channels having small cross-section, and the heat used during the travel of the fluid in the long channels permits the expansion of the fluid without changing the latter's temperature, so that the entire amount of the heat is transformed into and used as energy in the form of velocity. If the heat should increase the temperature of the fluid at full expansion to a point higher than the initial temperature, then this heat only delivers work in the usual way. It will also be seen that by my arrangement and combination of parts heat of a low temperature can be used, so that the running expenses are comparatively light. In order to run the apparatus very economically and with as small velocity as possible in the fluid, it is desirable to employ heavy gases as the motive agent.

By the use of such gases I obtain a higher ratio between the living force and the work of compression.

It is to be understood that free expansion 50 of the fluid begins with the inlet-pipe B and ends at the entrance of the buckets of wheel A; also, that the channels A⁴ are so proportioned to the passage that leads to them as to permit full expansion to take place in them 55 until the fluid passes into the buckets.

Free expansion is the condition of the fluid in which it can expand to the surrounding pressure without doing any work or putting other bodies in motion. In such condition 60 the velocity of the fluid is increased; but when putting other bodies in motion the fluid necessarily loses velocity proportionate to that acquired by the body set in motion, and consequently the fluid loses power or ability to 65 expand and its temperature cannot sink so low as it would have done if no body had been put in motion.

Having thus described my invention, I claim as new and desire to secure by Letters 70 Patent—

1. The combination of a source of gaseous motor fluid under pressure and an impact motor-wheel, means for permitting free expansion of the motor fluid before reaching 75 the motor-wheel, and means for heating said fluid during said expansion.

2. An apparatus of the class described, provided with a motor having a stationary disk formed with a series of passages, each terminating in a series of channels, to permit the gaseous fluid to pass through the passages and channels and expand freely in the latter, a heater connected with the said disk to heat the said fluid during the expansion period, 85 and a turbine wheel having buckets into which discharge the said channels, substantially as shown and described.

GUSTAF M. WESTMAN.
